UNITED STATES PATENT OFFICE.

CHARLES CHINNOCK, OF BROOKLYN, NEW YORK.

IMPROVED CORKSCREW.

Specification forming part of Letters Patent No. 35,362, dated May 27, 1862.

To all whom it may concern:

Be it known that I, CHARLES CHINNOCK, of Brooklyn, in Kings county and State of New York, have invented a new and Improved Mechanical Device for Drawing Corks; and I do hereby declare that the following is a full and exact description thereof, reference being had to the accompanying drawings, and to the letters of reference marked thereon.

Figure 1 represents the device in position to commence drawing the cork. *a a a* is the frame; *b b*, the screw and shaft in one piece; *c*, the shoulder; *d d*, the crank or handle. Fig. 2 represents the same with the cork drawn.

This invention is a simplification of all mechanical corkscrews, doing away with all combination screws, pinions, levers, or cams and using only the screw which pierces the cork as the power for lifting it.

When used, the frame *a* is placed on the top of the bottle, the shank and screw *b* is pressed down to enter the cork, and the crank *d* is then turned around, forcing the screw into the cork till the shoulder *c* strikes the top of the frame *a*. As the downward motion of the screw *b* is then stopped, the cork rises on the screw till it is drawn, as in Fig. 2.

What I claim as my invention, and desire to secure by Letters Patent, is—

The combination of the frame *a* with the screw *b* and shoulder *c*, substantially as and for the purpose specified.

CHS. CHINNOCK.
